(57) **CLAIM**

The ornamental design for the air pump set, as shown and described.

DESCRIPTION

FIG. 1 is a front, right, top perspective view of the first embodiment of the air pump set, showing my new design;
FIG. 2 is a rear, left, bottom perspective view thereof;
FIG. 3 is a front, right, top perspective view of the piece A of the air pump set;

FIG. 4 is a rear, left, bottom perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is a front, right, top perspective view of the piece C of the air pump set;

FIG. 12 is a rear, left, bottom perspective view thereof;

FIG. 13 is a front elevational view thereof;

FIG. 14 is a rear elevational view thereof;

FIG. 15 is a left side view thereof;

FIG. 16 is a right side view thereof;

FIG. 17 is a top plan view thereof;

FIG. 18 is a bottom plan view thereof;

FIG. 19 is a front, right, top perspective view of the piece D of the air pump set;

FIG. 20 is a rear, left, bottom perspective view thereof;

FIG. 21 is a rear, right, bottom perspective view thereof;

FIG. 22 is a front elevational view thereof;

FIG. 23 is a rear elevational view thereof;

FIG. 24 is a left side view thereof;

FIG. 25 is a right side view thereof;

FIG. 26 is a top plan view thereof;

FIG. 27 is a bottom plan view thereof;

FIG. 28 is a front, right, top perspective view of piece A and piece C in the first combined state;

FIG. 29 is a front, right, top perspective view of piece A and piece D in the first combined state;
 FIG. 30 is a front, right, top perspective view of piece A and piece C in the second combined state;
 FIG. 31 is a front, right, top perspective view of piece A and piece D in the second combined state;
 FIG. 32 is an enlarged view of detail 32 in FIG. 19;
 FIG. 33 is an enlarged view of detail 33 in FIG. 24;
 FIG. 34 is a front, right, top perspective view of the second embodiment of the air pump set, showing my new design;
 FIG. 35 is a rear, left, bottom perspective view thereof;
 FIG. 36 is a front, right, top perspective view of the piece B of the air pump set;
 FIG. 37 is a rear, left, bottom perspective view thereof;
 FIG. 38 is a front elevational view thereof;
 FIG. 39 is a rear elevational view thereof;
 FIG. 40 is a left side view thereof;
 FIG. 41 is a right side view thereof;
 FIG. 42 is a top plan view thereof;
 FIG. 43 is a bottom plan view thereof;
 FIG. 44 is a front, right, top perspective view of the piece C of the air pump set;
 FIG. 45 is a rear, left, bottom perspective view thereof;
 FIG. 46 is a front elevational view thereof;
 FIG. 47 is a rear elevational view thereof;
 FIG. 48 is a left side view thereof;
 FIG. 49 is a right side view thereof;
 FIG. 50 is a top plan view thereof;
 FIG. 51 is a bottom plan view thereof;
 FIG. 52 is a front, right, top perspective view of the piece D of the air pump set;
 FIG. 53 is a rear, left, bottom perspective view thereof;
 FIG. 54 is a rear, right, bottom perspective view thereof;
 FIG. 55 is a front elevational view thereof;
 FIG. 56 is a rear elevational view thereof;
 FIG. 57 is a left side view thereof;
 FIG. 58 is a right side view thereof;
 FIG. 59 is a top plan view thereof;
 FIG. 60 is a bottom plan view thereof;
 FIG. 61 is a front, right, top perspective view of piece B and piece C in the first combined state;
 FIG. 62 is a front, right, top perspective view of piece B and piece D in the first combined state;
 FIG. 63 is a front, right, top perspective view of piece B and piece C in the second combined state;
 FIG. 64 is a front, right, top perspective view of piece B and piece D in the second combined state;
 FIG. 65 is an enlarged view of detail 65 in FIG. 52; and,
 FIG. 66 is an enlarged view of detail 66 in FIG. 57.
 The dashed broken lines in the figures are for the purposes of illustrating portions of the air pump set that form no part of the claimed design.

The dash-dot-dash broken lines are for notating enlarged views and form no part of the claimed design.
